UNITED STATES PATENT OFFICE.

FREDERICK W. BENDER, OF CRYSTALLAKE, NEW JERSEY.

SHIPPING-CRATE.

No. 823,840.

Specification of Letters Patent.

Patented June 19, 1906.

Application filed August 1, 1905. Serial No. 272,147.

To all whom it may concern:

Be it known that I, FREDERICK W. BENDER, a citizen of the United States, and a resident of Crystallake, in the county of Bergen and State of New Jersey, have invented a new and Improved Shipping-Crate, of which the following is a full, clear, and exact description.

This invention relates to crates such as used in handling, storing, or shipping fruits and vegetables.

The object of the invention is to produce a crate of simple construction which will be extremely rigid and strong, and, furthermore, to provide an arrangement which will prevent the contents of the crates from being subjected to pressure when set up in piles as arranged in cars for shipment.

The invention consists in the construction and combination of parts to be more fully described hereinafter and definitely set forth in the claim.

Reference is to be had to the accompanying drawings, forming a part of this specification, in which similar characters of reference indicate corresponding parts in all the figures.

Figure 1 is a perspective of a crate constructed according to my invention, the cover 30 thereof being removed. Fig. 2 is a longitudinal section through the crate with a cover in position. Fig. 3 is a cross-section through the crate and showing the lower portion of a second crate set thereupon, the purpose of 35 this view being to illustrate an arrangement for preventing pressure upon the contents of the crates; and Fig. 4 is a horizontal cross-section taken at one of the corners of the crate.

Referring more particularly to the parts, 1 represents the body of the crate. This body is constructed with four corner-posts 2, of substantial material, and these posts are formed on opposite corners with rabbets or 45 vertical grooves 3. In this way longitudinally-disposed shoulders are formed on the post. The posts are connected with a plurality of horizontal slats or bars 4 and 5, the former being disposed longitudinally of the 50 crate and the latter constituting the end walls of the crate. These slats 4 and 5 after being attached in position, as shown, are secured in place by additional reinforcing-strips or battens 6, which are fastened over the ends 55 thereof, as shown. The outer faces of these reinforcing-strips 6 are flush with the outer

faces of the posts, as indicated. In this way a very firm and rigid construction is formed at the corners without rendering the appearance of the crate unsightly. The lowermost 60 of the slats 5 are designated 5^a, and these are of special construction, as indicated most clearly in Fig. 2. These slats are preferably of heavier construction than the others, and the inner face of each is provided with a rabbit 65 7 in such a way that oppositely-disposed shoulders 8 are formed. The bottom slats 9 of the crate rest upon these shoulders and are rigidly attached thereto by suitable fastening devices. In this way a space 10 is formed 70 beneath the bottom of the crate in the lower extremities of the posts 2.

A cover 11, of any suitable construction, is provided, the same being furnished on its inner face with transverse cleats 12, which assist in securing the cover in position. The advantage of elevating the bottom slats 9 lies substantially in the fact that when the crates are piled one upon the other, as indicated in Fig. 3, the bottom of the crate disposed above is not in contact with the contents of the crate disposed beneath. From this arrangement the contents of the crates are relieved of all pressure, and while this is beneficial, since it prevents injury to the 85 fruit, it is also an advantage in preventing any possibility of breaking the bottoms or covers of the crates. Thus the weight of the crates above is taken on the side walls of the crates below. 90

Having thus described my invention, I claim as new and desire to secure by Letters Patent—

A crate having corner-posts and longitudinally-disposed rabbets formed therein, vertical walls composed of horizontally-disposed slats having their ends attached in said rabbets, reinforcing-strips attached over the ends of said slats at said rabbets and having their outer faces flush with the outer faces of said 95 posts, an opposite pair of said slats having shoulders formed on the inner faces thereof above the lower extremities of said posts, and slats resting on said shoulders and constituting a bottom for said crate. 100 105

In testimony whereof I have signed my name to this specification in the presence of two subscribing witnesses.

FREDERICK W. BENDER.
